UNITED STATES PATENT OFFICE

FAIRBANK CARPENTER, OF CHICAGO, ILLINOIS, ASSIGNOR TO GEO. B. CARPENTER & CO.,
OF CHICAGO, ILLINOIS, A CORPORATION OF ILLINOIS

TENT

Application filed April 1, 1931. Serial No. 526,834.

My invention relates to improvements in tents and is particularly adapted to tents for play rooms, nurseries, and for use by children and the like, though it may be used in connection with larger tents. One object of my invention is to provide a tent which will be easily assembled and disassembled, which may be erected without pins or tie ropes and which will provide an entirely clear and unobstructed area throughout the entire tent enclosed by the walls thereof. Other objects will appear from time to time in the course of the specification and claim.

I illustrate my invention more or less diagrammatically in the accompanying drawings, wherein—

Figure 1 is a perspective of the tent;

Figure 2 is a plan view of the floor frame in the assembled position;

Figure 3 is a detail of the means for fastening the tent to the frame;

Figure 4 is a detail of the tent poles in a partially collapsed position;

Figure 5 is a detail of a modified form of frame partially assembled;

Figure 6 is a perspective view of a modified form of tent;

Figure 7 is a perspective of a modified form of frame partially collapsed;

Figure 8 is a perspective of the tent pole used with the tent of Figure 6; and

Figure 9 is a perspective of the ridge pole used with the tent of Figure 6.

Like parts are indicated by like symbols throughout the specification and drawings.

Referring first to the preferred form shown in Figures 1 to 4 inclusive the tent frame is made up of two straight bars A, A¹ hinged together by a fixed hinge A². There are two pairs of these bars assembled to make a rectangular frame and the two frame members are joined by a releasable hinge A³ having a removable hinge pin A⁴. The frame members A¹ are each centrally socketed and adapted to receive pins A⁵ on the lower ends of the two tent poles A⁶ which poles are hinged permanently at their upper ends at A⁷ and have inclined abutting surfaces A⁸ to limit their angular displacement so that the two surfaces A⁸ come together as shown in Fig-

ure 1 when the pins A⁵ are socketed in the frames A¹.

The tent is made up of three continuous triangular panels B, and one triangular panel B¹ which is slotted as indicated in line with the center of the panel and the apex of the tent. In line with an angle joining each two triangular sides are grommets B² which grommets may be hooked over pins B³ on the frame, the frame being preferably chamfered as indicated as at B⁴ so that the pin may come out through the grommet generally at right angles to the line of tension along the corner of the tent between the grommet and the apex. The two opposed edges of the slit of the triangular wall B¹ are associated with a hookless fastener B⁵ having operating handles B⁶ inside and outside, the canvas at one side of the slit being provided with a grommet B⁷ associated with a pin B⁸ on the frame. This slit provides the door to the tent. The grommet B⁷ and pin B⁸ are provided so as to hold the wall of the tent down to permit the operator to pull up on the hookless fastener member to slide it along the tent and permit separation of the two opposed edges. Assuming that the hookless fastener locking mechanism is at the top of its excursion the two edges of the panel B¹ may swing apart to form an open door and the whole canvas will as a result be more or less slack. If the hookless fastener is drawn down it will cam the two edges of the canvas together exerting a tension on the panel B¹ which tension will be transmitted through the other panels peripherally to make the tent tight.

In the modified form shown in Figure 5 the four frame members instead of being hinged together are provided each with an overlapping lug C rigidly mounted at the end of each frame member. The lug is apertured at C¹ in register with an aperture C² in the opposed frame member and a pin C³ may pass through the registering holes to hold the frame in position. The corners of the frame are chamfered as indicated at C⁴ and the pin C⁵ is placed at the chamfered portion of the ends of the two side frame bars C⁶. The bars C⁷ which carry the mem-

bers C are also apertured at C⁶ to engage the tent poles so that when the canvas is put in place the tension on the canvas will hold the bar C⁶ up against the under side of the member C and allow the whole tent to be lifted as a unit.

In the modified form shown in Figures 6 to 9 inclusive the tent is an A tent instead of a pyramid tent. Each frame half is made up of three sections, an end section D and two side sections D¹ D². Hinges D³ D⁴ join the three sections so that they may be collapsed as indicated in Figure 7. The two separate elements are adapted to be joined together by hinges D⁵ associated with removable pins D⁶. The tension of the canvas locks the frames in line. The end sections D are apertured as indicated at D⁷ to be engaged by pins D⁸ on the tent poles D⁹. Pins D¹⁰ on the other end of the tent poles engage sockets D¹¹ on the ridge pole D¹². The relation of the two tent poles and the ridge pole with the canvas cover is sufficient to hold the entire tent in proper assembled relation.

The canvas cover in this case instead of being made up of four triangular sections is made up of two triangular end sections E E and a central rectangular section E¹ joined to the two sides of the sections E and extending over the ridge pole. At one side of the tent the section E¹ is slit as at E² and associated with the hookless fastener E³. Grommets E⁴ are at the corners of the tent associated with pins E⁵ on the frame. A grommet E⁶ adjacent the slit is associated with the pin E⁷ for the same purpose as pointed out in connection with the form shown in Figure 1. The camming action of the hookless fastener is the same in each case.

The use and operation of my invention is as follows:

The tent is preferably shipped or stored in a bag. In assembling, the tent and the frame work are withdrawn from the bag. The frame work is unfolded and arranged with the four sides of the floor engaging frame assembled together to form a rectangular unit. The tent poles are inserted in the holes in the tent frame the poles meeting at the top over the center line of the frame and held together by the hinge and abutting ends as indicated, the pins on the ends of the poles being thrust into the openings in the floor frame. Then the tent canvas is opened and placed over the tent poles with the peak at the apex of the poles. The four corners of the tent are then fastened to the frame the grommets in the canvas being slipped over the four pins on the floor frame, the two triangles formed in the canvas on the two sides of the tent where the poles are located providing sufficient strength in tension to maintain the plane of the two poles perpendicular to the plane of the floor frame. The grommet associated with the side of the tent

where the door is disposed is also hooked over a fifth pin. When it is desired to open the tent for entrance the hookless fastener may be seized by the handle on the outside and lifted up thereby opening the door of the tent. The grommet and pin associated with the door is provided so that the operator may have something to lift up against in disengaging the fastener and will not be compelled to hold the tent down with the other hand. After the tent is opened the door grommet may be released if desired so that the whole side of the tent can be opened. For closing the door either from the inside or the outside the operator will seize either inside or outside handle and draw the hookless fastener down, thus, so to speak, camming the two opposed edges of the canvas on both sides of the door together and preferably the grommet will be hooked over the pin again so as to provide an abutment against which to pull when it is later desired to open the tent door.

The tent will stand up in its proper shape and position whether the door is open or not. However, when the door is open the tension on the canvas around the periphery of the tent along a line where a plane parallel with the floor intersects the tent wall will be reduced and there may be a certain amount of slackness in the tent walls. The hookless fastener with its camming action, draws the opposed tent edges together and exerts tension peripherally thereby holding the canvas tight when the door is closed.

In the form of A tent shown the frame is made up of two groups of three sections each, one section extending across each end and two frame sections pivoted or hinged to form the laterals. The end sections are socketed, the tent poles penetrate the sockets and project upwardly at the end of the tent to carry a ridge bar having sockets engaged by the pins on the tent pole. The canvas structure forms the bracing for the tent as before. The door in this case is located in the inclined central side of the tent.

I claim:

In a tent, in combination, a sill frame and a vertical frame, loosely articulated together, each frame comprising a plurality of loosely articulated rigid members, a fabric tent body attached to the sill frame about its lower edges, projecting upwardly therefrom and supported by the vertical frame, the frames and their articulated elements being held in working relation with one another and locked together by the tent fabric whereby the tent and frames may be handled when so locked together as a unit.

Signed at Chicago, county of Cook and State of Illinois, this 30th day of March, 1931.

FAIRBANK CARPENTER.
